Mitsui Chemicals Gets Ready to Bring Electronic Eyewear to market, announced Oct. 5, 2017, [online], [site visited Jul. 7, 2018]. Available from Internet, <URL: <https://www.japanchemicaldaily.com/2017/10/05/mitsui-chemicals-gets-ready-to-bring-electronic-eyewear-to-market/>> (Year: 2017)*

Primary Examiner — Michelle E. Wilson

Assistant Examiner — Sanjeev Paul

(74) *Attorney, Agent, or Firm* — Brundidge & Stanger, P.C.

CLAIM

The ornamental design for eyeglasses, as shown and described.

DESCRIPTION

FIG. 1 is a top front perspective view of eyeglasses showing our new design;

FIG. 2 is a front view of eyeglasses thereof;

FIG. 3 is a rear view of eyeglasses thereof;

FIG. 4 is a top view of eyeglasses thereof;

FIG. 5 is a bottom view of eyeglasses thereof;

FIG. 6 is a right side view of eyeglasses thereof;

FIG. 7 is a left side view of eyeglasses thereof;

FIG. 8 is a top front perspective view of eyeglasses showing our new design;

FIG. 9 is a front view of eyeglasses thereof;

FIG. 10 is a rear view of eyeglasses thereof;

FIG. 11 is a top view of eyeglasses thereof;

FIG. 12 is a bottom view of eyeglasses thereof;

FIG. 13 is a right side view of eyeglasses thereof;

FIG. 14 is a left side view of eyeglasses thereof;

FIG. 15 is an enlarged front perspective view of eyeglasses thereof; and,

FIG. 16 is an enlarged left side view of eyeglasses thereof. The dashed broken lines in the figures show portions of the eyeglasses that form no part of the claimed design.

The dot-dash broken lines in the figures show boundaries that form no part of the claimed design.
